UNITED STATES PATENT OFFICE.

EDWARD THOMAS, OF CLEVELAND, OHIO, ASSIGNOR TO THE AMERICAN STEEL AND WIRE COMPANY OF NEW JERSEY, A CORPORATION OF NEW JERSEY.

TAKE-UP BLOCK.

Application filed March 9, 1926. Serial No. 93,386.

This invention relates to take-up or drawing blocks for use in drawing metal and more particularly to take-up blocks for coiling metal which is delivered from cold rolls, although it is not limited to this use but may be used wherever drawing or take-up blocks are used.

One object of this invention is to provide a novel form of block of the character described which will automatically collapse when its rotation is stopped thereby facilitating the removal of the material therefrom.

Another object is to provide a block of the character described having novel means for gripping the end of the material to be drawn or wrapped on said block.

A further object is to provide a block having the novel construction, design and combination of parts hereinafter described and pointed out in the following specification and illustrated in the accompanying drawings.

In the drawings:

25 Figure 1 is a side elevation showing the take-up block in its relative position to a pair of cold rolls.

Figure 2 is an enlarged detail side elevation of the block.

30 Figure 3 is a sectional view taken on the line III—III of Figure 2.

Figure 4 is a sectional view taken on the line IV—IV of Figure 2.

Figure 5 is a sectional view taken on the line V—V of Figure 3.

Referring more particularly to the drawings, the numeral 2 designates the shaft of the block, which is journaled in a bearing 2^a on the take-up stand A, and upon which 40 the hub 3 is keyed. A drum portion composed of parts 4 and 5 is mounted around the hub 3. The part 4 of the drum is provided with bearings 6 and 7 and is mounted for free movement on the shaft 2. The part 45 5 of the drum has its one end provided with a sleeve portion 8 adapted to be aligned with openings 9 and 10 in the sides of the drum portion 4, and a pivot pin 12 is mounted in the openings 9 and 10 and sleeve 8 to form 50 a pivotal connection.

The drum parts 4 and 5 are provided adjacent their unconnected or open ends with pairs of lugs 13 and 14, respectively, between which pivot pins 15 and 16 are mounted. 55 Toggle levers 17 and 18 are pivotally con-

nected at one end to the pins 15 and 16, respectively, and have their other ends pivotally connected to a pivot pin 19. An operating link 20 has one end pivotally connected to the pin 19 and its other end pivotally connected to a lug 21 on the hub 3.

The toggle lever 18 is provided with a lug 22 to which one end of a strong coiled spring 23 is connected. A washer-like plate 24 is secured in the spring 23 adjacent its other end, and a headed bolt or rod 24^a is passed through said plate and through a lug 25 on the hub 3 and provided with a lock-nut 26 and adjusting nut 27 above the lug 25. It will be readily understood that by adjusting the position of the nuts 26 and 27 the tension of the spring 23 may be adjusted.

The part 4 of the drum is provided with an inwardly opening transverse slot 28 which has its one wall recessed to receive 75 an elongated dog or jaw bar 29. The bar 29 is provided with threaded apertures adjacent each end in which are threaded guide rods 30 which project through suitable apertures in the drum part into the interior of 80 the drum. Coiled springs 31 are mounted around each of the rods 30 and are held in position by washers 32 and nuts 33 threaded on the inner ends of the rods 30.

A jaw or dog operating rod 34 is threaded 85 into a suitable aperture in a lug 35 on the hub and projects through an opening in the drum part 4 into engagement with the bar 29. A set screw 36 is provided in the lug 35 to lock the rod 34 in adjusted position. 90

Suitable slots 39 are provided in the face of the drum to permit the passage of tie wires around the material wrapped on the drum to tie such material together before removing it.

The take-up block is provided with a brake composed of a drum 40 and brake-band 41. The drum 40 is bolted or otherwise secured to the part 4 of the drum and the band 41 is fitted around the drum 40. 100 The band 41 has one end provided with a threaded rod 42 on which is threaded a sleeve 43. An eye 44 is threaded in the sleeve 43 and is pivotally connected to a bracket 45 on the take-up frame A by a pin or bolt 105 46. The sleeve 43 forms means for adjusting the brake-band.

The other or movable end of the band is provided with a double eye member 47 rigidly secured thereto. A brake lever 48 has 110

its one end pivotally mounted on the pin or bolt 46 in the bracket 45 and the eye member 47 on the movable end of the brake band is connected to the lever 48 intermediate its 5 ends by a pin 49 so that when the outer or free end of the brake lever is depressed, the lever will move about the pin 46 and tighten the band 41 on the drum 42.

A coil spring 50 has one end fixedly connected to the bearing 2^a on the take-up frame and its other end connected to the outer free end of the lever 48 so as to normally hold the lever in raised or non-braking position. A foot-lever 51 has its rear end pivotally connected to a bracket 52 secured to the take-up frame A, and is connected intermediate its ends by clevis links 53 and 54 to the free end of the lever 48. An angle-shaped latch member 55 is mounted on the floor and provided with an opening 56 through which the foot-lever 51 projects. The opening 56 is offset at 57 to form a shoulder under which the foot-lever 51 is latched when depressed.

In operation, assuming that the block is in 25 closed or collapsed position, with the toggle operated ends of the drum parts 4 and 5 in engagement, and that material is to be wrapped on the block, the rod 34 will be adjusted to the proper length to force the 30 jaw 29 against the material. The end of the material will then be inserted in the slot 28 under the jaw 29. The brake foot-lever 51 will then be depressed to tighten the band 41 on the drum 40 and thus retard the movement 35 of the take-up drum when power is applied. Power will then be applied to rotate the shaft 2 and hub 3. The hub 3 will rotate a slight distance relative to the drum, thereby forcing the rod 34 against the jaw 29 40 to engage the end of the material, moving the link 20 toward an upright position to depress the toggle levers 17 and 18 and thereby expand or spread the drum parts 4 and 5, and stretching or tensioning the spring 23. 45 The brake serves to retard the movement of the drum until the jaw 29 has gripped the material to be wrapped on the block, and after the block has been extended, and about one revolution has been made the retarding effect 50 of the brake is no longer necessary, and it will be released by releasing the foot-lever 51. After the above operations are completed, the force of the rotating hub will be delivered through the rod 34, the link 20 55 and toggle levers 17 and 18, and spring 23 to the drum and cause rotation of the drum with the hub 3.

The rotation of the hub 3 relative to the drum is limited by the rod 34 and jaw 29 60 so that the link 20 is never moved into a dead center position. When the torque or power is released from the shaft 2 the rotation of the hub 3 is slowed down and the spring 23 will automatically cause a relative movement 65 of the drum parts 4 and 5 relative to the

hub which will collapse the toggles 17 and 18 to collapse the drum parts, and move the jaw 29 away from the rod 34, thereby allowing springs 31 to retract the jaw from engagement with the material on the drum. 70

After the drum is collapsed, the material may be tied together in a bundle by passing tie wires through the slots 39 in the face of the drum and around the material. The tied bundle of material may then readily be 75 removed from the collapsed drum.

It will be understood that it is not always necessary or desirable to employ a brake to retard the operation of the take-up drum and that if desirable such brake may be 80 omitted.

While I have shown and described one specific form of my invention, I do not wish to be limited thereto, since various modifications may be made without departing 85 from the scope of my invention which is defined in the appended claims.

I claim:

1. A take-up or drawing block comprising a shaft, a hub secured to said shaft, a drum portion formed in two parts, one of the parts of said drum being freely mounted on said shaft, the other of said drum parts being hinged at one end to said first mentioned drum part, and having its other end connected by a series of toggle levers with said hub and said first mentioned drum part, a spring connected to one of said toggle levers and said hub and adapted to normally urge said levers into collapsed position, said toggle levers being adapted to be forced into extended position to expand said drum parts into operative position against the tension of said spring when said shaft and hub are rotated, and means operable by said hub for automatically gripping the material being drawn on said block when said hub and shaft are rotated. 100

2. A take-up or drawing block comprising a shaft, a hub secured to said shaft, a drum portion formed in two parts, one of the parts of said drum being, freely mounted on said shaft, the other of said drum parts being hinged at one end to said first mentioned drum part, and having its other end connected by a series of toggle levers with said hub and said first mentioned drum part, a spring connected to one of said toggle levers and said hub and adapted to normally urge said levers into collapsed position, said toggle levers being adapted to be forced into extended position to expand said drum parts into operative position against the tension of said spring when said shaft and hub are rotated, and means operable by said hub for automatically gripping the material being drawn on said block when said hub and shaft are rotated, said gripping means being adapted to automatically release the material when said drum parts are collapsed. 110

3. A take-up or drawing block comprising a shaft, a hub secured to said shaft, a drum portion formed in two parts, one of the parts of said drum being freely mounted on said shaft, the other of said drum parts being hinged at one end to said first mentioned drum part, and having its other end connected by a series of toggle levers with said hub and said first mentioned drum part, 10 and a spring connected to one of said toggle levers and said hub and adapted to normally urge said levers into collapsed position, said toggle levers being adapted to be forced into extended position to expand said drum parts 15 into operative position against the tension of said spring when said shaft and hub are rotated.
4. A take-up or drawing block comprising a shaft, a hub secured to said shaft, a drum portion formed in two parts, one of the parts of said drum being freely mounted on said shaft, the other of said drum parts being hinged at one end to said first mentioned drum part, and having its other end 20 connected by a series of toggle levers with said hub and said first mentioned drum part, a spring connected to one of said toggle levers and said hub and adapted to normally urge said levers into collapsed position, said 25 toggle levers being adapted to be forced into extended position to expand said drum parts into operative position against the tension of said spring when said shaft and hub are rotated, and a material receiving slot and gripping means in said first mentioned drum part, and means operable by said hub for operating said gripping means.
5. A take-up or drawing block comprising a shaft, a hub secured to said shaft, a drum portion formed in two parts, one of the parts of said drum being freely mounted on said shaft, the other of said drum parts being 30 hinged at one end to said first mentioned drum part, and having its other end connected by a series of toggle levers with said hub and said first mentioned drum part, a spring connected to one of said toggle levers and said hub and adapted to normally urge 35 said levers into collapsed position, said toggle levers being adapted to be forced into extended position to expand said drum parts into operative position against the tension of said spring when said shaft and hub are rotated, and a material receiving slot and gripping means in said first mentioned drum part, and means operable by said hub for operating 40 said gripping means.

In testimony whereof, I have hereunto signed my name.

EDWARD THOMAS.
